COMBINED ASHTRAY AND TOILET PAPER HOLDER

Michael M. Graham, 2635 23rd St.,
Santa Monica, Calif. 90405

Filed July 26, 1971, Ser. No. 166,334

Term of patent 14 years

Int. Cl. D6—06

U.S. Cl. D6—91

FIG. 1

FIG. 3

FIG. 1 is a perspective view showing a combined ashtray and toilet paper holder showing my new design;

FIG. 2 is an elevational view taken from the side opposite that shown in FIG. 1; and

FIG. 3 is a top plan view thereof.

I claim:

The ornamental design for a combined ashtray and toilet paper holder, substantially as shown.
